United States Patent Office

Des. 189,480
Patented Dec. 27, 1960

189,480

TROPHY BASE

Michael J. Albanese, Chicago, Ill., assignor to Dodge,
Inc., Chicago, Ill., a corporation of Illinois

Filed Jan. 15, 1959, Ser. No. 54,190

Term of patent 14 years

(Cl. D29—23)

I claim:

The ornamental design for a trophy base, as shown.
